UNITED STATES PATENT OFFICE.

JOHN J. FARGUE AND ROBERT W. SMITH, OF SAN FRANCISCO, CALIFORNIA; SAID FARGUE ASSIGNOR TO SAID SMITH.

STAMP-AFFIXING DEVICE.

SPECIFICATION forming part of Letters Patent No. 743,263, dated November 3, 1903.

Application filed October 9, 1902. Serial No. 126,433. (No model.)

To all whom it may concern:

Be it known that we, JOHN J. FARGUE and ROBERT W. SMITH, citizens of the United States, residing in the city and county of San Francisco, State of California, have invented an Improvement in Stamp-Affixing Devices; and we hereby declare the following to be a full, clear, and exact description of the same.

Our invention relates to a device for affixing stamps to letters and packages.

It consists of a receptacle or carrier for the stamps, which are contained thereon in long strips, a mechanism for withdrawing the stamps from the carrier and transferring them into a horizontal position above the point where they are to be attached, mechanism for detaching a single stamp from the strip, mechanism for moistening the surface, and mechanism for pressing the stamp upon the moistened surface.

It also comprises details of construction, which will be more fully explained by reference to the accompanying drawings, in which—

Figure 1 is a side elevation. Fig. 2 is a vertical section. Figs. 3 and 4 are side views showing different positions of the roller-carrying arms.

As shown in the accompanying drawings, A is a yoke or frame of any suitable form or description adapted to carry the operating mechanism of the apparatus. Across the upper part of this frame is a horizontal shaft 2, upon which is carried a hollow drum or receptacle 3, within which a strip of stamps may be coiled. One side of this drum is opened sufficiently to allow the strip to pass through a sort of a guide-pin, as 4, and thence it passes between the rollers 5, which are journaled across the lower part of the frame. These rollers may be rubber or other suitable surfaces, so that the stamps passing between them may be pressed upon sufficiently to be advanced by the revolution of the rollers at the proper intervals. One of these rollers is here shown as having its shaft journaled in fulcrumed bell-crank levers 6, pivoted upon each side of the frame, and by means of springs 7 a tension is produced upon these levers which holds the roller yieldingly against

the other roller and provides a constant and sufficiently frictional contact to advance the stamps. The rollers are here shown as having their axes in a vertical plane, so that when the stamps pass between them they are advanced horizontally.

8 is a horizontal vertically-movable plate having pins projecting from each of its corners and extending through slots 9 in the sides of the frame A. These pins moving in the slots serve as guides in which the plate may rise and fall.

8^a represents springs to return the plate after being depressed.

10 is a stop-plate against which the advancing edge of a stamp is arrested when it has reached the proper point and is ready to be severed and applied to the letter or package.

11 is a slotted plate adjacent to the feed-rollers 5, through the slot in which the stamps are advanced, and when the stamp has thus been advanced across the space beneath the plate 8 the latter, fitting closely between the plates 10 and 11 and having a sharp corner moving contiguous to the plate 11, will act to sever the stamp from the remainder of the roll and at the same time press it down and apply it to the surface. In order to cause the stamp to adhere, it is necessary to apply moisture to either the stamp or the surface. It is objectionable to moisten the stamp, because the moisture will interfere with the proper application of the stamp, while causing them to sometimes adhere to the presser. We have therefore designed a means for moistening the surface to which the stamp is to be applied. This means consists of a roller 12, the shaft 13 of which passes through slots 14 in opposite sides of the frame and is journaled in the lower ends of pivoted swinging arms 15. These arms are here shown as pivoted and turnable about the shaft 2. The arms are preferably telescoped or formed in two parts, the lower part 15^a being slidable upon the upper portion 15^b, as shown, so that the journals of the roller 12 may move in the horizontal slot 14, while the arms swing about their pivot-point, and the roller will thus travel horizontally across the surface to which the stamp is to be applied.

The various mechanisms are to be operated as follows: 16 is a vertically-slidable portion, here shown in the form of a rectangular yoke, having the horizontal top and vertically-slotted sides which are movable outside of the frame A, and the shaft 2 passes through the slots 17 of the yoke, thus forming a guide for the lower end, while the upper or horizontal portion of the yoke is perforated and is 10 slidable upon the stem 18, which is fixed to the top of the frame A. In order to reciprocate the yoke 16, we have shown a handle 19, fixed to the top of the yoke, and within this handle and within the hollow stem 18 is a 15 spring 20, which normally acts to raise the yoke and which may be compressed, when pressure is brought upon the handle 19 so that the yoke 16 may be pushed down with relation to the frame A by hand-pressure 20 and will be returned to its normal position by the action of the spring 20. When the yoke is pushed down, the lower edges of its side member strike suitable pins projecting from the plate 8 through the slots 9 and carry 25 said plate downward with the yoke.

The shaft of the upper roller 5 is here shown as provided with a pinion 21 on the outer end, and this is engaged by a gear-wheel 22, mounted upon a shaft journaled 30 horizontally in the frame and above the rollers 5. This shaft also carries a ratchet-wheel 23, and this ratchet-wheel is engaged by a toothed rack 24, the upper end of which is pivoted to the slidable yoke 16, as shown at 25.

35 26 is a spring pressing against the back of the rack 24 to hold it in light contact with the ratchet 23, so that when the handle is pushed down, carrying with it the sliding yoke 16, the teeth of the ratchet-bar 24, engaging 40 the ratchet 23, will turn it with its shaft and gear 22, and through its connection with the pinion 21 the feed-rollers 5 will also be turned and a stamp advanced across the space above the package to which it is to be applied.

45 When the handle is released and the spring 20 acts to raise it and the yoke, the spring 26 yields and allows the rack-bar 24 to move freely over the teeth of the ratchet 23, thus returning without rotating the ratchet.

50 In order to operate the moistening-roller 12, a lever-arm 27 projects at right angles from the upper part of the lever 15^a, and in line with this arm a pin 28 is carried by the slidable yoke 16, so that when the yoke is raised 55 by the action of the spring 20 the pin 28 will be brought into contact with the arm 27 and will swing the lever-arm 15 15^a so as to move the roller from the position shown in Fig. 4 to the one shown in Fig. 2 across the surface 60 of the package to which the stamp is to be applied. As soon as the handle and sliding yoke are depressed a spring 29, which is connected with the lever 15, acts to draw it back again to the position shown in Fig. 4.

65 Between the vertical plate 10 and the outside of the casing A is a chamber which contains a moistening-sponge or other means of

moistening the roller 12, as shown at 30. The lower part of the plate 10 is cut away or so disposed as to allow the roller 12 to pass into contact with the moistening substance within the chamber, and the surface of the roller being formed of felt or other suitable absorbent will be sufficiently moistened by this contact, so that it is always ready to be advanced 75 across the surface and to moisten it sufficiently to receive a stamp, being returned each time by the return movement of the slide. In this manner the stamps may be rapidly and mechanically affixed to letters or packages of 80 any description.

The normal position of the roller 12 is to the right of the apparatus, as shown in Figs. 1 and 2; but when the handle 19 is depressed the spring 29 will cause the roller to 85 travel over into the space between the rear wall of A and the vertical wall 10 to be moistened through capillary attraction of contact with the sponge. In actual operation if the machine has stood any length of time the first reciprocation would simply move the roller across the stamping-chamber without wetting the paper and the severed stamp would be saved and stuck on in the ordinary manner. If the roller is very dry, the handle 95 would be held down a moment until the roller would be moistened sufficiently. Thereupon the moistening, severing, and sticking the stamps would go on in the manner contemplated. These devices, it is understood, are generally used where there are a great many letters to be stamped at one time. The reason why the roller works in the way shown rather than in the opposite direction is that it is desired to move the roller 12 entirely outside the path of movement of the plate 8, which cannot well be done if the roller 12 was 100 to rest underneath rollers 5 when the cutter 8 was descending.

Having thus described our invention, what we claim, and desire to secure by Letters Patent, is—

1. A stamp-affixing device consisting of a frame, a stamp-receptacle contained therein, guides over which the stamps are led and feed-rollers between which they are adapted to pass horizontally through the lower part of the frame, pivoted bell-crank levers on the outer sides of the frame having springs connected with one of the arms, and the journal-shafts of one of the feed-rollers turnable in the other whereby an adjustable pressure-feed is obtained, a vertically guided and slidable yoke, a ratchet-bar having one end pivoted to the yoke and the other loose, a spring 115 pressing against the back of the bar, a ratchet mounted upon one of the feed-roller shafts and gearing through which motion is transmitted to rotate the rollers by the depression of the sliding yoke and a spring by which the 120 yoke is returned when released.

2. A stamp-affixing device consisting of a frame, having slots horizontally across its lower portion, a stamp-container located with-

in the frame, feed-rollers between which the stamps are led, a vertically guided and slide-able yoke and rack-and-ratchet mechanism actuated thereby to revolve the rollers, and 5 a roller located in the lower part of the frame and adapted to pass across the surface to which the stamp is to be affixed, and to moisten said surface, and a shaft passing through the roller and having its ends mounted to 10 slide in the horizontal slots of the frame.

3. A stamp-affixing device consisting of a frame, feed-rollers journaled thereon, a stamp-containing receptacle, guides by which a strip of stamps is delivered between the feed-rollers, a vertically guided and slide-able yoke, rack-and-ratchet mechanism through which motion is communicated to rotate the feed-rollers when the yoke is depressed, a plate 15 fixed to the frame and spaced from one wall thereof to form a moisture-containing receptacle located in the lower part of the frame, a horizontally-guided transversely-movable absorbent-roller adapted to receive and transmit moisture, said roller having a 20 shaft and said frame having its sides provided with horizontal slots in which the ends of said shaft slide, and swinging lever-arms in the ends of which the roller-shaft is journaled and contact-arms by which the levers 25 are moved to cause the roller to travel across the surface.

4. A stamp-affixing device consisting of a main frame, having feed-rollers journaled therein, a stamp-containing receptacle, mechanism by which the rollers are turned and stamps delivered across the lower part of the frame, a moisture-containing receptacle located upon one side of the lower part of the frame, an absorbent-roller, a spring by which 35 it is drawn in contact with the moisture-receptacle, and fulcrumed levers in the ends of which the roller-shaft is journaled, said levers having projecting arms, and a slide-able yoke having pins adapted to contact with the 40 arms and move them so as to cause the roller to travel across the surface to be moistened.

5. A stamp-affixing device consisting of a frame, a stamp-containing receptacle therein, feed-rollers journaled in the frame between 45 which the stamps are led, a vertically-reciprocating yoke and rack-and-ratchet and intermediate mechanism whereby the rollers are turned to advance the stamps at each reciprocation of the yoke, a spring-retracted 50 absorbent-roller guided and movable transversely across the lower part of the frame

and adapted to moisten the surface to which the stamps are to be affixed, telescopic lever-arms in the lower ends of which the moistening-roller shaft is journaled, the upper ends 60 of the arms being pivoted, and contact-arms by which the levers are moved to cause the roller to traverse the surface when the yoke is depressed.

6. A stamp-affixing device consisting of a frame, feed-rollers journaled therein, a vertically-guided slide-able yoke, a rack-and-ratchet mechanism actuated by the reciprocation of the yoke to turn the rollers and advance the stamps, a moistening-roller movable transversely over the surface and connections by which it is actuated by the movement of the yoke, a spring normally tending to draw the roller into contact with the moistener said roller held against the power of said spring 75 by the upward or normal position of the yoke, and a vertically-slide-able pressure-plate beneath which the stamps are delivered, said plate acting to sever each stamp from the roller and to apply it to the moistened surface. 80

7. A stamp-affixing device consisting of a frame having a moistening-chamber, feed-rollers journaled on one side of the lower part of the frame, a stamp-receptacle and guides 85 by which the strip of stamps is delivered to be advanced by the feed-rollers, a vertically-guided yoke, rack-and-ratchet connections whereby the rollers are turned by the depression of the yoke, a vertically guided and movable plate and vertical walls between which it is movable, one of said walls having a horizontal slot registering with the space between the feed-rollers, whereby the stamps are projected therethrough beneath the plate, a 90 moistening-roller, means controlled by the yoke for holding the roller away from the moistening-chamber and a spring tending to normally draw the roller toward said chamber and by which it is caused to traverse the 95 surface to which the stamp is to be applied, the vertically-moving plate acting to shear each stamp from the roll where it is projected through the slot in the vertical wall and to apply it to the surface. 100

In witness whereof we have hereunto set our hands.
